UNITED STATES PATENT OFFICE.

MATES WITART, OF WATERBURY, CONNECTICUT.

WATCHMAKER'S LATHE.

1,160,353.

Specification of Letters Patent. Patented Nov. 16, 1915.

Application filed June 26, 1915. Serial No. 36,584.

To all whom it may concern:

Be it known that I, MATES WITART, a subject of the Emperor of Russia, residing at Waterbury, in the county of New Haven 5 and State of Connecticut, have invented a new and useful Improvement in Watchmakers' Lathes; and I do hereby declare the following, when taken in connection with the accompanying drawings and the characters 10 of reference marked thereon, to be a full, clear, and exact description of the same, and which said drawings constitute part of this application, and represent, in—

Figure 1 a front view of a watch makers' 15 lathe constructed in accordance with my invention. Fig. 2 an end view of the same. Fig. 3 a top or plan view. Fig. 4 a side view of the lathe chuck with the index device removed. Fig. 5 a sectional view on the line 20 *a*—*b* of Fig. 1. Fig. 6 a sectional view on the line *c*—*d* of Fig. 3.

This invention relates to an improvement in watch maker's lathe, the object being to combine in a compact and convenient manner with an ordinary lathe, means for tapping, milling and other cutting such as is commonly necessary for watch and clock makers; and the invention consists in the construction hereinafter described and particularly recited in the claims.

In carrying out my invention, I employ the usual form of lathe bed 2 on which is mounted for longitudinal movement a lathe head 3. This bed is removably mounted on 35 a vertical post 4 extending into a block 5 suitably mounted upon a bed plate 6. In one side of this post 4 is a rack 7 to be engaged by a pinion 8 mounted on a shaft 9 which carries a worm wheel 10 engaged by 40 a worm 11 on a worm shaft 12 which extends to one side of the machine where it is provided with a knurled handle 13 by which the worm may be turned to raise and lower the post 4. The post may be firmly 45 locked in any position of adjustment by a set screw 14. In rear of the lathe bed and mounted upon the bed plate 6 is a bench or table 15 supporting a frame 16 in which a driving shaft 17 is mounted and adapted 50 to be driven through a pulley 18 from any source of power and preferably provided at the opposite end with a hand wheel 19. On the shaft is a cone pulley 20 from which a belt may run to a cone pulley 22 on a chuck 55 sleeve 23 carrying the usual chuck 24 operated through a spindle 25 in the usual man-

ner. Also mounted on the driving shaft is a bevel gear 26 meshing with a bevel pinion 27 on a milling shaft 28 which projects outward over the lathe beds 2 and carries a 60 milling tool or cutter 29. This gear wheel is provided with a belt groove 30 to carry a belt 31 to a pulley 32 on a tool carrier or chuck 33. The cutter and tool carrier are mounted on a slide 34 longitudinally movable in a frame 16 and the slide is connected by a link 35 with a crank-disk 36 mounted on a shaft 37 having a beveled head 38 engaging with a recess 39 formed in the disk 36, the shaft 37 being drawn rearward by 70 a spring 40, and the shaft is provided at its outer end with a thumb nut 41 for adjusting the tension of the spring. This shaft 37 extends through a sleeve 42 fixed to which is a worm wheel 43 meshing with a worm 44 75 on a shaft 45 extending toward the frame 16, this shaft being in gear connection with the driving shaft so that as the driving shaft revolves the crank-disk 36 will be turned so as to move the slide toward and from the 80 lathe head with more or less pressure according to the tension placed upon the spring.

Preferably and as shown, I employ an index feed for the chuck sleeve. This consists of a plate 46 mounted on the chuck sleeve and held against rotation by means of a stop pin 47 projecting outward from the lathe head into a notch 48 in the plate. The plate is formed with a segmental slot 49 in which is adjustably mounted a stop 50. On a flanged bushing 51 in the plate is a lever 52 guided by the slot 49 against the tension of a spring 53. This lever carries a spring pawl 54 adapted to engage 95 with the teeth of an index wheel 55 which is mounted on the flanged bushing 51 so as to impart movement to the chuck sleeve. Pivotedly mounted on the plate is a detent spring pawl 56 engaging with the teeth of 100 the index wheel to prevent the retrograde movement. The pawl on the lever is adapted to engage and advance the teeth, while the other pawl rides over the teeth in an advanced position but holds it against retrograde movement, and the index wheel may be advanced a predetermined number of teeth determined by the location of the stop pin 50.

While the cutter and tool carrier may be 110 driven together, one or the other may be cut out. Thus the tool carrier may be cut out

by removing the belt 31, or the cutter may be thrown out of action by sliding the bevel gear 26 out of mesh with the beveled pinion 27, the beveled pinion being feathered to 5 the driving shaft 17 and may be locked in engagement with the bevel pinion 27 by means of a latch 57 engaging with a notch 58 in the hub of the bevel gear or held out of engagement with the bevel pinion by the 10 engagement of the latch 57 with the groove 59 in the hub. If, for instance, it is desired to cut teeth for a pinion the blank will be mounted in the chuck in the usual way and the chuck head lowered as shown in Fig. 15 1 of the drawings so as to properly present the edge of the blank to be cut against the cutting or milling tool; and as the mechanism is driven the milling tool will be advanced and retired across the edge of the 20 blank to be cut, it being understood that the blank is held against rotation. The blank may then be advanced to a predetermined extent according to the number of teeth to be cut through the movement of the index 25 wheel 55 until the pinion is complete. If it is desired to drill this same blank as for cannon pinions, or the placing of pawls, or for any other purpose, the lathe head will be elevated into line with the tool carrier which 30 will then be advanced toward and from the work in the same way and perform the necessary operation of drilling, tapping or turning. If it is desired to revolve the work, then the pulleys 20 and 22 will be connected 35 by a belt so as to cause the chuck to revolve and the work may be suspended between the chuck and the tool carrier in the ordinary manner of lathes; or the drill may be mounted in the lathe chuck and the work mounted 40 in the tool carrier. I thus provide in a simple and convenient way means for holding work and advancing the cutter, drill or other instrument to it, or provide for rotating the work, and when the tools are ad-

vanced they are always advanced under a 45 friction feed which may be adjusted to the desired tension.

I claim:—

1. A watch makers' lathe comprising a 50 lathe bed, a frame, a slide in said frame and carrying operating tools, a friction crank-disk, and connections between said crank-disk and slide for moving said slide.

2. A watch makers' lathe comprising a 55 lathe bed and head, a frame, a slide in said frame carrying working tools movable with said slide, a crank-disk, a link connecting the disk with the slide, a sleeve on which said disk is mounted, and means for adjusting the friction between the disk and the 60 sleeve.

3. A watch makers' lathe comprising a 65 lathe bed and head, a frame in rear of said lathe bed, a driving shaft mounted in said frame, a slide mounted in said frame, said slide carrying operating tool holders, connections between the driving shaft and said tools, whereby they are rotated, a crank-disk, connection between the disk and slide, said disk mounted on a sleeve, said sleeve 70 adapted to be turned by said driving shaft, and means for adjusting the tension between the disk and said sleeve.

4. A watch makers' lathe including a 75 lathe head and chuck sleeve, of a plate connected with said head, an index wheel connected with said sleeve, a lever, a pawl connected with said lever and adapted to engage and advance said index wheel, a pawl 80 adapted to engage with said wheel to prevent retrograde movement, and a stop adjustably mounted on said plate in the path of said lever.

MATES WITART.
